UNITED STATES PATENT OFFICE.

WILLIAM O. BEMENT, OF WORCESTER, MASSACHUSETTS, ASSIGNOR TO THE WIRE GOODS COMPANY, OF SAME PLACE.

SWAGING MACHINERY.

SPECIFICATION forming part of Letters Patent No. 555,721, dated March 3, 1896.

Application filed May 23, 1894. Serial No. 512,210. (No model.)

To all whom it may concern:

Be it known that I, WILLIAM O. BEMENT, a citizen of the United States, residing at Worcester, in the county of Worcester and 5 Commonwealth of Massachusetts, have invented certain new and useful Improvements in Swaging Machinery, of which the following is a specification.

The object of my invention is to provide a 10 machine in which a metallic rod of indefinite length may be cut into a number of pieces of uniform size, each of which may be swaged any desired part of its length. The machine is one in which the rod, while being swaged, 15 has both rotary and longitudinal motion and receives a series of blows on its surface between properly-constructed dies. In this respect it is to be distinguished from that class 20 of swaging machinery in which the stock is not turned, but in which the swaging-dies are placed in a revolving head and act toward a common center.

In the drawings, Figure 1 is a plan view of the machine, also showing in detail the construction of the chuck-bearing shaft. Fig. 2 is a side elevation showing the manner of operating the knuckle-joint which controls the cam-carriage and throws the cam-head in and out of connection with the roller which actuates the swaging-die shown in plan in Fig. 1, and also shows the lever which operates the chuck which holds the rod being swaged, and also operates the mechanism for cutting said rod to the desired length, as will more 30 clearly appear hereinafter. Fig. 3 is an end elevation showing the nut, by engagement with which longitudinal action of the chuck-bearing shaft is secured, and the manner of throwing the nut out of connection with said shaft, and means by which the main shaft 2 35 is thrown out of connection with the other working parts of the machine, so that the latter may be automatically stopped at any desired point. Fig. 4 is an end view on the line 45 4 4, Fig. 1, which shows the knuckle-joint thrown up and the cam-head pulled back out of contact with the roller which actuates the swaging-die, the cam-head being in such a position that as it revolves it does not touch the roller. Fig. 5 is an end view covering the details shown in Fig. 4, the knuckle-joint

being thrown down and the cam-head in contact with the roller which actuates the swaging-die, and the various parts of the machine being shown in their relations when at work. 55 Fig. 6 is an end view through the line 6 6, Fig. 1, showing the half-nut engaged with the thread of the chuck-bearing shaft and the tripping-cam and lever operated by it, which through connecting mechanism throws up the 60 knuckle-joint and disconnects the cam-head with the roller actuating the swaging-die, as shown in Figs. 1, 2, and 4. Fig. 7 illustrates the parts shown in Fig. 6, their relations only being changed, and shown as they appear 65 when the half-nut is out of contact with the chuck-bearing shaft and the tripping-cam has operated upon the lever. Figs. 8 and 9 are side views of the chuck-lever and chuck-head, showing the friction-cam on the end of the 70 lever-arm which regulates the friction between the chuck-bearing shaft and the bed of the machine. Fig. 10 is a front view of the chuck, showing the bell-shaped opening in which the rod to be swaged is inserted. 75

In Fig. 1, A is the bed of the machine, which may be mounted upon legs or upon a table, as may be found most convenient.

1 is a pulley which may receive power by means of a belt from the main shaft. The 80 pulley 1 is mounted upon a shaft 2, the end of which is shown, which shaft is mounted in suitable boxes 3 4 upon a movable cam-carriage 5, and the shaft may be kept in continuous operation whether the other working 85 parts of the machine are in operation or not.

The cam-carriage is connected at its rear end by means of a knuckle-joint at the point 6 with the plate 7, which is secured to the rear of the bed of the machine, and in such a manner that when the knuckle-joint is raised, as in Fig. 4, the cam-head 8 mounted upon the shaft 2 is thrown out of contact with the roller 9, through which the swaging-die 10 mounted upon a suitable way is actuated. 90

The movable die 10 is opposed by a similar die 11, which I prefer to have stationary, although it may be movable.

The cam-head 8 may be so constructed as to give any required number of blows during 100 each revolution of the main shaft.

In practice I prefer to construct my ma-

chine as shown in the drawings, to give four blows for each revolution.

At the opposite end of the shaft 2 from the main pulley 1 is the pulley 12, which has frictional contact regulated by the spring 59 and movable box 64 with the pulley 13 upon the shaft 14, so that when these pulleys are in contact the shaft 14 may be revolved. Upon the opposite end of shaft 14 is a gear-wheel 15, which meshes with the gear-wheel 16, which operates the chuck-bearing shaft 17, which revolves continuously while the swaging mechanism of the machine is in operation. The chuck-bearing shaft 17 is mounted in suitable boxes 18 19, the former of which is secured to the bed of the machine and the latter of which may be moved longitudinally in properly-constructed ways on the bed of the machine.

The chuck 20 is mounted upon the end of the shaft 17 and contains a holding and cutting-off device, both of which are operated by the same means and in the same way. The holding device is operated by the lever 21, pivoted at 22, and depressed or elevated by means of the collar 23, actuated by the lever 24. (Shown in Figs. 2, 8, and 9.) At its opposite end the lever 21 bears upon the pin 25, which, when the opposite end of the lever is elevated, bears upon one part of the split bushing 26, which is thus brought in contact with the rod 27, which is being swaged, and which is shown in outline in Fig. 1. The other part of the split bushing 28 is stationary.

The lever 29 is constructed and operated the same as lever 21, and operates the cutter 30, so that when the end 31 of the lever is elevated the cutter acts upon the rod 27, severing it at the required point.

It will be seen that the movable part 26 of the bushing is a flat piece, while the stationary part 28 is a right-angled piece, the rod passing through a hole in its base. This construction makes it possible to fit the stationary part 28 of the bushing firmly in the chuck-head, affording a rigid bearing against which the cutter 30 may act.

The shaft 17 is most conveniently made hollow, so that the rod, cut into parts of any required length, may be pushed through the shaft, as shown.

It will be noted that when the cutter 30 acts upon the rod and severs it the natural consequence would be that the unsecured portion of the rod would be pushed out of the path of the part that follows it, and hence could not be pushed through the chuck-bearing shaft. To overcome this difficulty I insert a spring 32 in the chuck-head, which pushes the severed portion of the rod back into position, so that it may be pushed through the chuck-shaft by the part of the rod which follows it.

The longitudinal movement of the shaft 17 is secured by means of the half-nut 33 in the arm 34 adapted to engage with a thread upon the shaft, so that when the two are in contact the shaft 17 has a positive longitudinal mo-

tion, which ceases when the two are thrown out of contact. This is done by elevating the handle 34 of the nut-arm, as shown in Fig. 7. When the nut engages with the thread upon the shaft 17 the tendency would be to pull the nut-arm laterally were it not for the shoulder 63 securely fastened to the bed of the machine, which holds the nut-arm in place.

The machine is so constructed that the longitudinal motion of the chuck-bearing shaft is regulated automatically and in the following manner: The movable box 19 is provided with a projection 35, which embraces the rod 36, which is loosely mounted in the boxes 37 38. As the carriage 19 travels along with the chuck-bearing shaft, the projecting piece 35 strikes the shoulder 39, and the rod 36 is moved longitudinally in its bearings until the end 40 strikes the downwardly-projecting end 41 (shown in Fig. 3) of the rocker-shaft 42. This throws back the overhanging hook 43, held in position by the spring 60, out of contact with the nut-arm 33, which leaves the spring 44 free to lift the handle 34, and thus throw the nut out of contact with the thread upon the shaft 17 and stopping the longitudinal motion of the latter.

The rotary motion of the shaft 17 continues somewhat longer than the longitudinal motion, but is also automatically stopped, and in the following manner: It will be noted upon referring to Fig. 3 that if the nut-arm 33 is elevated, lifting the nut out of contact with the shaft 17, the opposite end 45 of the nut-arm, pivoted at 46, is depressed, as shown in Fig. 7, and the tripping-piece 47, loosely mounted in the end 45 of the nut-arm and held in position by the spring 61, is brought into such relation to the lever-arm 48 that the tripping-cam 49, which is mounted on the shaft 14, coming in contact with the rear end of the tripping-piece 47, forces its outer end into contact with the lever 48, as shown in Fig. 7, the result being that the lever is pushed forward, and hence the rod 50 is drawn to the right.

Upon turning to Fig. 2 it will be noted that the end of rod 50 is connected with rod 62, through the opposite end of which runs the rod 52, which operates the knuckle-joint 6. The rod 52 is provided with a shoulder or collar 51, which, when the machine is in operation, has a bearing upon the under side of the rod 62, as shown in the drawings, Fig. 2. When, however, the rod 50 is drawn to the right, as explained in connection with Fig. 3, the rod 62 is sufficiently moved from its normal position to release the shoulder 51 from its bearing. The spring 53 is then free to act and pushes up the rod 52. This elevates the knuckle-joint 6 and throws the cam-head 8 out of contact with the roller 9, actuating the swaging-die 10, and also throws friction-wheel 12 out of contact with friction-wheel 13, and thus stops the rotary motion of shaft 17.

The knuckle-joint is depressed by means of the treadle 54, pivoted at 55 and shown in Fig. 3, and connected, as shown, with the rod

52. When the lever is depressed, the shoulder 51 is drawn down through the opening in the end of the rod 62 and secures a bearing, as shown in Fig. 2, the clutch and cam-head 5 taking the position shown in Fig. 5, thus putting in operation all the working parts of the machine, excepting the mechanism for imparting longitudinal motion to the shaft 17. This is effected at the pleasure of the operator by engaging the nut with the thread upon shaft 17 by depressing the nut-handle 34, as shown in Fig. 6.

It will be noted that the pulley 1 and the main shaft 2 are in continuous operation, 15 whether the other working parts of the machine are running or not, and the other working parts of the machine are started and stopped at pleasure by depressing or elevating the knuckle-joint, which controls the movement of the cam-carriage, and by engaging the nut with the thread upon shaft 17.

This machine is designed to cut from a rod of indefinite length any required number of pieces, which may be swaged any required 25 part of their length, leaving the unswaged portion of each piece longer or shorter, as may be required. Each piece is severed from the rod after the operation of swaging is completed, and, as has been explained, the same 30 operation which grips the rod preparatory to starting the swaging mechanism severs the piece which has been swaged. Consequently it is essential to have some means for accurately fixing the length of the unswaged portion of each piece. This is effected by means 35 of the stop 56, Fig. 1, which is adjustable, but can be secured to the outer edge of the bed of the machine at any desired point, and the stop is fixed at a point which, when the longitudinal 40 movement of the shaft 17 has ceased, as already explained, shall be removed from the nearest side of the box 19 a distance equal to the united lengths of the abutting unswaged portions of two pieces of the rod. After 45 one piece has been swaged, and before the chuck-carriage is moved forward to its original position to repeat the operation, the carriage is moved back until the side of the box 19 strikes the stop 56. The hold of the chuck 50 upon the wire is then loosened, as shown in Fig. 8, and the carriage moved forward into the position for starting, as shown in Fig. 1. The lever 24 is then moved forward, as shown 55 in Fig. 9. This not only grips the rod tightly, but at the same time severs the piece which has been swaged, leaving the unswaged end of the cut piece and the unswaged end of the uncut piece which follows it of the desired length.

In order that the rod may be held while the chuck-carriage is being moved forward after a piece has been swaged, I arrange at the opposite end of the bed of the machine the clutching device 57, which holds the rod securely and prevents it from moving when it is not held in the chuck.

In order that the chuck-carriage 19 may not

move too freely, it is provided with a friction device (illustrated in Figs. 8 and 9) acting through the lever 24, which operates the 70 clutching and cutting levers 21 29. The lever 24 at its lower extremity is provided with a cam 58, and when the machine is in operation and the arm 24 is thrown forward, as shown in Fig. 9, the friction device is brought 75 into operation.

Having described the details of my machine, I will proceed to describe its mode of operation.

The end of a rod of any desired length is 80 passed into the mouth of the chuck and secured in place by throwing forward in the position shown in Fig. 9 the handle actuating the gripping and cutting-off levers 21 and 29. By this operation the rod is firmly secured 85 and at the same time the end is cut off square. The knuckle is thrown into working position, as shown in Fig. 5, by depressing the lever 54. (Shown in Fig. 3.) The swaging-dies at once begin to operate, and rotary motion is 90 imparted to the shaft 17, and through the friction-pulleys 12 and 13 to the gear-wheels 15 16. Longitudinal motion may be given to the shaft 17 at the pleasure of the operator by depressing the handle 34 and engaging the half-nut 95 with the thread upon the chuck-shaft. In practice it is preferable to allow the shaft to rotate several times before longitudinal motion begins to insure a smooth finish upon the rod being swaged. Longitudinal motion having 100 been imparted to the shaft 17, it is continued as long as may be necessary, and is adjusted automatically, as before explained, by means of the rod 36 and the shoulder 39. The rod having been swaged the required distance, 105 the working parts of the machine are automatically thrown out of operation, as described. The box 19 is moved back in contact with stop 56, to fix the length of the unswaged portion of each piece. Then the shaft 17 is 110 moved back to its original position, and the operation is repeated. The shaft 17 being hollow, the completed rods are by the movement of the shaft to and fro naturally and regularly delivered without intervention on 115 the part of the operator at the rear end of the shaft.

It is obvious that the shaft 17 is made hollow to permit of cutting a rod of indefinite length into shorter pieces and reducing them 120 in size, as desired. The machine could, however, be successfully run having a solid shaft; but were this done each piece swaged must be cut before it is placed in the machine, thus making the process slower and less economical.

Having thus described my invention, what I claim as new, and desire to secure by Letters Patent, is—

1. In a swaging-machine, a shaft carrying 130 a cam adapted to actuate a movable swaging-die, and mounted in a reciprocatingly-movable carriage, in combination with a swaging-die and intermediate, movable die, whereby

said movable die may be brought to rest without stopping the cam-carrying shaft substantially as shown and described.

2. In a swaging-machine, a shaft mounted in a movable carriage, and carrying a pulley, in combination with a shaft adapted to hold a metallic rod, and an intermediate shaft, actuated by said pulley, whereby rotary motion may be imparted to said rod-carrying

10 shaft, substantially as shown and described.

3. In a swaging-machine, a shaft, carrying a cam and a pulley, and mounted in a movable carriage, in combination with a shaft adapted to hold a metallic rod, and to receive 15 rotary and longitudinal motion, and an intermediate shaft actuated by said pulley, whereby rotary motion may be imparted to said rod-carrying shaft and the rod subjected to the action of the swaging-dies, substantially as 20 shown and described.

4. In a swaging-machine, a shaft, carrying a cam and a pulley, and mounted in a movable carriage, in combination with a hollow shaft, adapted to receive rotary and longitudinal motion, and provided with a chuck 25 adapted to hold a rod, said chuck being also provided with cutting mechanism, whereby a portion of the rod may be subjected to the action of the swaging-dies, and then severed 30 from the unswaged portion of the rod, and with an intermediate shaft actuated by said pulley, whereby rotary motion may be imparted to said hollow shaft, substantially as shown and described.

35 5. In a swaging-machine, a shaft, carrying a cam and a pulley, and mounted in a movable carriage, in combination with a hollow shaft, adapted to receive rotary motion in the manner specified, and provided with a thread 40 upon its exterior surface, adapted to engage with a nut whereby longitudinal motion may be imparted to said shaft, and provided with means for holding a rod, whereby the latter may be subjected to the action of the swag- 45 ging-dies and delivered at the rear end of said hollow shaft, substantially as shown and described.

6. In a swaging-machine, a shaft adapted to receive rotary and longitudinal motion in 50 the manner specified, in combination with a chuck, adapted to hold a rod, and provided with cutting mechanism whereby the ends of the rods may be cut to exact length, substantially as shown and described.

55 7. In a swaging-machine, a hollow shaft adapted to receive rotary and longitudinal motion in the manner specified, in combination with a chuck adapted to hold a rod, and provided with cutting mechanism whereby a 60 portion of the rod may be subjected to the ac-

tion of the swaging-dies, and then severed from the unswaged portion of the rod, substantially as shown and described.

8. In a swaging-machine, a hollow shaft, adapted to receive rotary and longitudinal motion in the manner specified, in combination with a chuck adapted to hold a rod, and provided with cutting mechanism whereby a portion of the rod may be subjected to the action of the swaging-dies, and then severed 65 from the unswaged portion of the rod, and with mechanism whereby said rotary and longitudinal motion may be automatically stopped, substantially as shown and described.

9. In a swaging-machine, a hollow shaft, 70 adapted to receive rotary and longitudinal motion in the manner specified, in combination with a chuck adapted to hold a rod, and provided with cutting mechanism whereby a portion of the rod may be subjected to the action of the swaging-dies and then severed 75 from the unswaged part of the rod, and a spring whereby the severed portion may be restored to its normal position in line with the unswaged part of the rod, and pushed through 80 the hollow shaft, and mechanism whereby said rotary and longitudinal motion may be automatically stopped, substantially as shown and described.

10. In a swaging-machine a hollow threaded 85 shaft, provided with a chuck, and adapted to receive rotary and longitudinal motion, as specified, and having a bearing in a movable box, in combination with a stop attached to the bed of the machine adapted to contact 90 with said box, whereby the length of the unswaged portion of each rod may be regulated before it enters the hollow shaft, substantially as shown and described.

11. In a swaging-machine a hollow shaft and 95 mechanism for imparting to the same rotary and longitudinal motion, in combination with a chuck adapted to hold a rod and provided with cutting mechanism, whereby said rod 100 may be clamped and a portion of it simultaneously severed, substantially as described.

12. As an improved mechanism, a chuck of the construction specified, containing in combination with a cutter a bushing composed of two parts, one of which is movable, whereby 110 the pressure upon the rod to be held may be regulated, and the other of which is stationary, affording a bearing, against which the cutter may act, whereby the rod may be severed, substantially as shown and described. 115
